UNITED STATES PATENT OFFICE.

SIDNEY O. BIGNEY, OF ATTLEBORO, MASSACHUSETTS, ASSIGNOR TO S. O. BIGNEY & COMPANY, OF ATTLEBORO, MASSACHUSETTS, A CORPORATION OF MASSACHUSETTS.

BRACELET CHAIN.

Application filed February 18, 1927. Serial No. 169,231

This invention relates to a bracelet chain having a series of flexible units connecting hooks at its opposite ends for attaching the bracelet chain to the bails of a wrist watch or the like; and the object of this invention is to provide a bracelet, the link units of which may be extended all in the same direction and having end hooks differently constructed one to be connected to one of the relatively slidable members of the link unit at one end of the bracelet, and the other of the relatively slid- 10 able members of the link unit being connected to a hook at the opposite end of the bracelet.

A further object of the invention is the pro- 15 vision of simple and effective means for connecting together the separable ends of the hook of the slide member of each link.

With these and other objects in view, the invention consists of certain novel features of 20 construction, as will be more fully described, and particularly pointed out in the appended claim.

In the accompanying drawings:

Figure 1 is a side elevation of my improved 25 bracelet construction connected to the bails of a wrist watch.

Figure 2 is a perspective view of one of the link units of the bracelet in extended position.

Figure 3 is a perspective view of the detach- 30 ing hook for one end of the bracelet.

Figure 4 is a perspective view of the detach- 35 ing hook at the opposite end of the bracelet.

Figure 5 is a plan view of the bracelet as- 40 sembled in extended position.

Figure 6 is a central sectional side view of 45 the hook attached to one end of the bracelet.

Figure 7 is a central sectional side view of 50 the hook attached to the opposite end of the bracelet.

Figure 8 is a perspective view showing one 55 construction by which the separable parts of the slide link may be detachably connected together.

Figure 9 is a top view of this link.

Figure 10 is a section on line 10—10 of 60 Figure 8.

It has heretofore been customary where expanding link units have been employed to 65 provide a connection at the center of the bracelet to dispose these link units in opposite directions from the center of the bracelet and provide end hooks which are similarly constructed to be attached to the same kind of a 70 link of the units at each end of the bracelet,

and in order to avoid the necessity of so connecting the units at the center that they may be expanded in opposite directions, I have provided end hooks differently constructed, one constructed to be attached to the guide or 60 body member of the link unit and the other to the hook or slide member of the link unit, whereby the link units may be disposed in the same direction throughout the length of the bracelet to form a like appearance throughout 65 the length of the bracelet, also it is found of advantage to lock together the ends of the detachable hook of the slide members of the links; and the following is a detailed description of the present embodiment of this invention and showing one means by which these 70 advantageous results are obtained:

With reference to the drawings, 10 designates a wrist watch having bails 11 to which the flexible connecting link units 12 may be 75 connected by means of end hooks 13 and 14. Each of the link units 12 comprises a body member 15 in which a link 16 slides endways relative thereto. A spring 17 acts between these two link members urging them to contracted position. The slide member 16 is in substantially band shape and split as at 18 adjacent one end with portions 19 overlapping portion 20, the latter of which is sufficiently 80 resilient to be pressed inwardly when the members of the unit are in expanded position to permit detachment of or attachment to the cross bar 21 of the body member of an adjacent unit. As will be seen from Figure 5, the link units are all in expanded position 85 and all similarly arranged end to end so that a chain of links of similar appearance throughout the length of the bracelet is presented and the units so connected present the slide member 16 at one end to be attached to 90 the end hook 13 and the body member 15 at the opposite end to be attached to the opposite end of hook 14, but in order that the different hooks may be formed to be readily attached to these differently constructed 95 links, I have formed the hook 13 with a body portion 22 slotted at its rear end as at 23 to provide a cross bar 24 which is of a similar size to that of the cross bar 21 of the body member of the link unit so as to readily receive 100 the attaching hook of the band-shaped slide member by passing the bar 24 through the split portion 18 thereof. The opposite hook 14 is provided with an integral tongue 25 extending from the top wall thereof which may 105 110

be folded about the bar 21 of the body link of a unit to firmly screw this link thereto, as illustrated in Figure 6.

Each of the end hooks is provided with a resilient tongue 26 with spring means 27 to hold the same in position but permit the tongue to yield sufficiently to be hooked into the bail 11 of the wrist watch.

It will be seen that I have provided a bracelet construction which may be expanded, the link units of which are similarly arranged to be expanded all in the same direction by which no break in the continuity of the bracelet while in extended position is presented to the eye thus enhancing the appearance of the same.

In some instances, it is found of advantage to provide means for locking together the ends of the slide link at the split 18 to strengthen the same and prevent these portions from separating under a heavy strain and to accomplish this in a simple and effective way, I have formed a dovetail-shaped projection 28 on the end of the spring tongue 29 and a correspondingly shaped recess or pocket 30 on the overlying portion 31 to receive this projection, whereby when in en-

gagement these parts are capable of withstanding an excessive endways tension without separating.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

A bracelet comprising a series of connected units, each unit comprising a body member and a slide member movable relatively thereto from one end only thereof, each of said units being disposed to permit the slide member to extend in the same direction from the body member, similar hooks connected to the end units of the bracelet, one hook having a tongue folded about the body member, and the other hook having a loop through which the slide member passes whereby each of said units is extendible in the same direction and the end hooks are attached to relatively different parts of the end units.

In testimony whereof I affix my signature.
SIDNEY O. BIGNEY.
